UNITED STATES PATENT OFFICE.

HOWARD GRIFFITH SHORTT, OF CARTHAGE, NEW YORK, ASSIGNOR OF ONE-HALF TO STEBBINS ENGINEERING AND MANUFACTURING COMPANY, OF WATERTOWN, NEW YORK, A CORPORATION OF NEW YORK.

AUTOMATIC RECEIVER PUMP.

Application filed December 17, 1927. Serial No. 240,661.

My invention relates to certain new and useful improvements in automatic receiver pumps, and more particularly to that class of pumps exemplified in my co-pending application for Letters Patent for automatic receiver pumps, filed Nov. 18, 1926, Serial No. 149,159, and my other copending application for Letters Patent for automatic receiver pumps, filed April 8, 1927, Serial No. 181,950.

Such pumps are designed chiefly for handling high temperature condensate, boiler feed water and the like; being adapted for use with air, steam, water, gas and all other kinds of gases, fluids and liquids; the device serving in connection with a steam condensation plant, a hot water heating system, a water distribution apparatus, or other mechanisms having similar purposes.

The present novel means are applied in connection with a single receiver, tank or reservoir; and a single control valve of the slide valve type actuates the high pressure steam inlet and exhaust valves of the receiver, said control valve being arranged in conjunction with a pair of expansion bellows, diaphragms, chambers or units, so as to introduce pressure thereinto in alternation, so that one bellows may actuate the high pressure steam valve to close the same and the other may actuate the exhaust valve to close the same, said valves being arranged to open alternately under the action of steam against them when the closing pressure is relieved. And it is found most effective to provide an operative relation for the steam and exhaust valves such that at the receiver-discharging period the exhaust valve will close before the steam valve opens, and at the receiver-filling period the steam valve will close before the exhaust valve opens, so as to prevent steam from blowing through. Thus I provide a novel and ingenious disposition and construction of the steam and vent valves for the receiver, so that they may be separately closed by means of pressure-actuated diaphragms; together with automatic devices in the receiver controlled by the level of the water therein for positively operating the control valve and causing it to allow pres-

sure to flow to one or the other expansion unit so as to effect a closing of the steam and exhaust valves, and their opening in proper sequence, in order that the receiver may be discharged of its aqueous contents when full by introducing high pressure steam thereinto against said contents, and may be relieved of such steam or water-expelling pressure when the receiver has been emptied of its aqueous contents to permit it to immediately fill up again, all in regular, serial, automatic alternation. And the invention may also be said to consist moreover in numerous details and peculiarities in the construction, arrangement and combination of parts, substantially as will be hereinafter described and claimed.

In the accompanying drawing illustrating my invention:

Figure 1 is a front elevation of my improved automatic receiver pump, with certain parts in section.

Figure 2 is a vertical section of the same in a plane through the central control valve at right angles to the front view of Figure 1, and taken on line 2, 2, of Figure 1.

Figure 3 is a view showing a side elevation of the valve mechanism, with the receiver or tank in longitudinal section.

Similar characters of reference designate corresponding parts throughout all the different figures of the drawing.

A tank, receiver, reservoir, or receptacle of any kind, is denoted by A. Said receiver may be mounted on a base A¹. This receiver may be of any size, shape, design or character, and may be taken by way of example as arranged with a steam condensation plant. The water of condensation flows into the receiver A through the opening a; and at the proper time when the receiver is full the water is discharged from the tank through the same opening a. Suitable check valves (not shown) are arranged in connection with the intake and discharge systems connecting at a² for example with the pipe a¹ which enters the receiver and has the opening a in the end thereof. The pipe a¹ may be curved as shown so as to bring the mouth a quite near the bottom of the 100

tank and establish an effective water seal.

The automatic pumping of the receiver A is accomplished through the agency of high pressure steam which enters the top 5 of tank A through the inlet port F after the tank has been completely filled up with water. The introduction of steam pressure against the water when the tank is full has the function of ejecting the water through 10 the combined inlet and outlet passage at a; and after this is done the expelling steam is vented to the atmosphere or elsewhere through the same port F, through which it entered the receiver and through 15 the vent or exhaust valve; therefore, so that receiver A will be in condition to refill again with water at a. Tank A has a removable head plate B bolted thereto by bolts b, or otherwise secured. The head plate B carries 20 thereon the control and inlet and outlet valve mechanism which I shall presently describe. Also it is formed on the side nearest the tank A with an elongated steam supply port D, having an inlet port d, 25 through which port d a steam supply valve introduces steam into the long port D in order that it may flow to the receiver; and the head B is also formed with an elongated discharge or venting port C for the exhaust steam after it has been used in expelling the water, the same having an outlet port c through which the exhaust steam is passed from the port C to atmosphere by means of a steam exhaust or vent valve. The ports 30 C and D merge together into the union port E which connects them both with the receiver port F, through which at one time live high pressure steam from port D enters the receiver and at another time the exhaust 35 or used steam is allowed to escape into vent port C, all as I shall fully describe in detail. Obviously when steam from the boiler under boiler pressure enters port D to fill the receiver it will also fill port C, but it will not pass to atmosphere as exhaust steam until the vent valve opens to allow all the steam used at the time in the receiver to vent to atmosphere after the high pressure valve has closed.

I will first describe the inlet and outlet valves for admitting live or high pressure steam to the receiver when it is full of water and for disposing of such steam when the receiver is empty of water after its ejection. These two valves are quite similar in construction and arrangement. They are closed separately by the action of a pressure-operated mechanism directed by a control valve; and they are both opened separately by the 60 action of steam or other pressure in lifting them at the time that the closing pressure has been released or reduced.

51 denotes the high pressure steam inlet valve; and 54 denotes the steam exhaust valve. Valve 51 has a long stem 49 on the

top side, and a short stem 52 on the other side, and the valve is contiguous to port d and functions in relation to a seat 57. Valve 54 has a long stem 47 on the upper side, and a short stem 55 on the other side, 70 and this valve is contiguous to port c and functions in relation to a seat 58.

The steam admission valve 51 is carried at the left hand on receiver head B, see Figure 1, and the steam vent valve 54 is supported at the right hand on receiver head B, see Figure 1, but of course this arrangement and location need not be strictly adhered to, but any other arrangement may be adopted to serve the same purposes. 75

Steam inlet valve 51 has a casing 34 that is bolted at 34^a, or otherwise secured to head B. Within the casing 34, the vertically movable valve 51 is arranged in relation to its seat 57 with respect to which it plays back and forth and controls communication between a lower chamber 61 in casing 34 and an upper chamber 62 in said casing. The lower chamber 61 is provided with a steam inlet supply pipe nozzle 60 on side 80 of casing 34, which nozzle allows connection with a pipe conveying high pressure steam from the boiler or some other point in the steam line to chamber 61 below valve 51, from which chamber the valve 51, when 85 lifted by the high pressure of the steam, delivers steam into upper chamber 62, wherein is port d, so that steam may pass out through this port, d, into the long port D, and thence into receiver A. Casing 34, 100 has a cover 41, bolted or secured thereon and fashioned with a bearing for the upper valve stem 49, which is suitably packed at 43 where it emerges from its bearing, a screw cap 44 being used to make a tight 105 joint above said bearing. The lower valve stem 52 below valve 51 slides in a short recess in lower end of casing 34. Thus the chamber 61 below valve 51 is constantly 110 filled with live steam, which lifts and opens the valve 51 to allow steam to pass for use when the mechanism that holds the valve to its seat at certain other times releases its hold for the time being and permits the valve to open. 115

The outlet or exhaust valve 54 for the low pressure steam after it has done its work in the receiver of ejecting the contents, is quite similar in construction and operation to the live steam valve 51 just described. It has a casing 35 that is bolted at 35^a or otherwise screwed to head B, in which casing is the valve 54 which is vertically movable with relation to its seat 58 with respect to which it plays back and forth and controls 120 communication between a lower chamber 63 in casing 35 and an upper chamber 53 in said casing. The upper chamber 53 is provided with a nozzle 56 on side of casing 35, to which may be connected a pipe for carry- 125 130

ing off the exhaust or vented steam or to allow venting directly into the atmosphere. From this chamber 53 the valve 54 when lifted by the pressure of the exhaust steam 5 under valve 54 in chamber 63 delivers to outlet 56. In chamber 63 is port *c* through which the exhaust steam is delivered from receiver through long port *C* into chamber 63. Casing 35 has a cover 42 secured there- 10 on and fashioned with a bearing for the upper valve stem 47 which is suitably packed at 45 where it emerges from its bearing, a screw cap 46 being used to make a tight joint above said bearing. The lower short 15 valve stem 55 below valve 54 slides in a short guiding recess in lower end of casing 35. Thus the chamber 63 below valve 54 is constantly filled with steam pressure through port *c*, which lifts and opens the 20 valve 54 to allow exhaust steam to pass out to atmosphere when the mechanism that holds valve 54 to its seat at certain times releases its hold for the time being. In the 25 operation and functioning of these steam and exhaust valves it will be noted that the steam inlet valve closes tightly before the steam outlet valve opens, and conversely.

I pass now to describe the control valve which controls the pressure which operates 30 the steam inlet and outlet valves I have just described, through the medium of expansion members. This is clearly shown in the sectional view in Figure 2; while the connecting pipes and other parts are delineated 35 fully in Figure 1. 1 denotes a cylinder or casing which is effectively supported on receiver head *B* by any suitable means. Within this casing or cylinder 1 is a close-fitting bushing 7 wherein slides up and down vertically a slide valve 8. This valve 8 is a block having a long lateral port 9 on one side, and on the opposite side having ears 65, to which a flat spring 19 is pivoted, the ends of which spring bear against the 40 bushing and are closely tensioned so as to hold the valve 8 tightly against its seat on the bushing. The ears 65 straddle the section 20 of valve rod 16 between the collars 17 and 18, the distance between which collars 50 is longer than the vertical length of valve 8 so as to allow play and permit the rod to move freely up and down, at one time shifting the valve downwardly and at another shifting it upwardly, these movements of 55 the valve opening and closing certain ports as I shall specify, but the valve stem has considerable up and down movement without affecting the valve for when the float is dropping the valve stem will lift more or 60 less without moving the valve, but when collar 18 strikes the valve 8 it will lift it to its upper position which may be termed the filling position; and when the float is rising it will pull down the valve stem more or less without moving the valve 8 until the

collar 17 strikes the valve and moves it down into its lower position which is called its discharge position.

The upper end of cylinder 1 is closed by a screw plug 5, having an inner central recess 64, that receives the upper end 66 of valve rod 16 and guides the same during its reciprocatory movements. And the lower end of cylinder 1 is closed by a screw cap 6, through which the rod 16 passes, said rod being packed at this point by suitable packing held in place by a gland 21 which is secured by a screw cover 22.

The cylinder 1 is filled with steam, air, or other pressure, through a pipe 4 which enters the wall of the cylinder and delivers into the interior of the cylinder through port 67 in bushing 7, said pipe 4 running from some suitable source of fluid or liquid pressure as a steam boiler or other power. In the wall of cylinder 1, are three ports 13, 14, and 15, which coincide respectively with three contiguous ports 12, 11, and 10, in the bushing 7 at seat of slide valve 8. Ports 11 and 14 constitute an exhaust outlet through which exhaust pressure fluids exit into pipe 36 which discharges into the atmosphere or elsewhere. Top ports 10 and 15 lead into pipe 40 which runs to the bellows or diaphragm 3 that actuates the exhaust valve 54; and bottom ports 12 and 13 lead into pipe 39 which runs to the bellows or diaphragm 2 that actuates the live steam valve 51. When the slide valve 8 is in its upper or filling position as shown in Figure 2, the passage 9 in the slide valve will connect port 10 with the exhaust outlet at port 11, or in other words the vent-valve operating bellows 3 will be connected with the discharge; while at the same time the port 12 will be uncovered by valve 8 and full operating pressure will be passing into steam-valve operating diaphragm 2. When the valve 8 is shifted however from its upper to its lower or discharge position, its lateral port 9 will connect port 12 with exhaust port 11, at the same time uncovering the upper port 10, so that steam-valve operating pressure from the interior of diaphragm 2 will pass to the discharge, while vent valve operating pressure will flow out of the interior of cylinder 1 into ports 10 and 15 and on into the diaphragm 3, whose function is to close the vent valve.

The two diaphragms 2 and 3 are hollow expansion members, like an expansion joint, and may be like a bellows or similar corrugated or accordion-like expansible means of flexible thin steel or other suitable material that will provide an expansible chamber, whose expansion will occur when it is filled with air, steam, or other pressure, and which will contract when the pressure is released from the interior of said expansible chamber. One of these corrugated bellows, as 2

is entered by pipe 39, and it is supported in a frame 37, mounted on the live steam valve casing 34, or the bearing head 41. The lower end of bellows 2 has a block 50, provided with a pocket to receive loosely the upper end of a steam-valve stem 49. Thus the valve stem 49 is separate from the bellows 2 that depresses it at certain times to close the valve. The other corrugated bellows, as 3, is entered by pipe 40, and it is supported in a frame 38 mounted on the exhaust valve casing 35, or bearing head 42. The lower end of bellows 3 has a block 48 provided with a pocket to receive loosely the upper end of vent valve stem 47. Thus the stem 47 is separate from the bellows 3 that depresses it at certain times to close the valve. These bellows or diaphragms 2 and 3 have an area in the interior ends which carry members 48 and 50 that bear a certain ratio to the faces of valves 51 and 54 that are exposed to pressure beneath, said bellows area being several times the area of the valves, so as to regulate the opening and closing pressures as will be afterwards more fully set forth. Thus we have expansion units for closing the valves, the same being actuated by pressure entering same from the control cylinder and governed by the control slide valve.

The receiver head B may have any desired form, size and shape, so that it may be convenient for disposing thereon and therewith many of the features of my invention. Thus it has a protuberant front portion 26 ending in a box-shaped member forming part of the receiver, see Figure 2, and connecting therewith through an opening 28, which accommodates the movement of a rearwardly extending bent rod 27 which carries a float G, so that as the float rises and falls due to the change of the water level it will move the rod 27 up and down. The front end of the projecting box member has an opening 45 covered by a plate 30, removably secured by means of bolts 31. The rod 27 is connected to a short horizontal shaft 29 which is supported in bearings in the projecting part 26, and has external retaining nuts 59 on the opposite ends; and the end rod 27 is cleft or slotted at 33 to engage a horizontal pin 32 in the lower end of the vertical valve rod 16 belonging to the control valve. This rod, already above described, projects below the cylinder 1 and enters the enlarged member 26 through a screw plug 25 which is screwed into member 26. The plug 25 carries a bearing for this rod, which is tightly packed by suitable means held in place by a gland 24 covered by a screw cap 23. The lower end of rod 16 has a threaded section and nut thereon to regulate its effective length, as shown.

When the tank is full of water and the float G has risen to the top, the lever 27

will have pulled down on the valve stem 16 so that collar 17 will have descended and engaged slide valve 8, with the effect of drawing down said valve into discharge position until its port 9 unites the ports 12 and 13 with the exhaust ports 11 and 14, at the same time opening ports 10 and 15 to receive full pressure from interior of cylinder 1. This operation of the slide valve therefore empties high pressure steam valve bellows 2 and thus allows the steam valve 51 to lift and open because of the steam pressure under it, so that live steam will pass through port D to the receiver on top of the full aqueous contents of the same, expelling such contents through opening a; while at the same time the opening of ports 10 and 15 to receive the full pressure in cylinder 1 will cause such pressure to expand vent valve bellows 3 and thus tightly close the vent valve 54. Vent valve will close before steam valve opens. Now as the live steam forces the water out of the receiver A the float drops and through action of the lever 27 the control valve stem 16 rises. When the receiver is empty and the rod 16 has lifted far enough to raise the control valve 8 to its high or filling position, as shown in Figure 2, the ports 12 and 13 will be opened to receive the full pressure of steam or air in the control cylinder 1, and the ports 10 and 15 will be connected with exhaust ports 11 and 14, so that pressure in vent valve expansion bellows 3 will escape. The contraction of bellow 3 will allow an opening of the vent valve 54 and allow the steam that now fills the receiver to exhaust to atmosphere, while the simultaneous expansion of the bellows 2 will close the live steam valve 51 and prevent any more high pressure steam from entering receiver A at this time. Steam valve closes before vent valve opens. Thus the receiver being now discharged can again refill with condensation or other water. And these series of processes will repeat themselves as fast as the receiver fills and then pumps out its contents, the operation being wholly automatic.

This is the general character of the operation, but it is necessary to describe the same in somewhat greater detail than this, because to obtain the best results it is essential that at the discharging period when the valves are put in position for the discharging operation, the vent valve should close before the high pressure valve opens, and at the filling period when the valves are put in position for the filling operation, it is essential that the high pressure steam valve should close before the vent valve opens, for this sequence of operation eliminates the chance of any blowing through in the different positions.

Referring again to Figures 1 and 2 it will be noted that the valves and receiver are all in the position taken when the receiver is

being filled. The control slide valve is up, that is in filling position, the float is in the bottom of the receiver, the receiver is empty of water but full of steam that has just entered, the vent valve is open to atmosphere, the steam valve is closed, the vent valve bellows is contracted, the steam valve bellows is expanded, so that the high pressure on vent valve bellows is being vented to atmosphere through action of float-controlled slide valve, and at the same time the high pressure in control cylinder of say 125 pounds is being applied to the steam valve bellows, holding steam valve closed against the high pressure steam coming through pipe 60. For example we will suppose that the high pressure under steam valve 51 is now 125 pounds, and the receiver pressure under vent valve 54 is practically zero pounds, or only enough to lift the vent valve when the bellows 3 contracts.

Now the float at once begins to rise as the water flows into the bottom of the receiver and float continues to rise as receiver continues to fill. Of course, the rising of the float reverses the direction of movement of the stem of control valve 8 and when the collar on it strikes valve 8 it proceeds to drop, or to assume discharge position, and as soon as ports 10 and 15 are opened a pressure of 125 pounds will be applied to the vent valve bellows. There being practically no pressure now except receiver pressure under this valve a building up of a few pounds, say six pounds in vent valve bellows will close the vent valve, whereas the pressure in the high pressure valve bellows must vent down approximately 22 pounds before the 125 pounds underneath this high pressure valve can force the same open due to the difference in areas between the valve and the interior of the bellows. This assures us that the vent valve will close first, or before the steam valve opens to admit steam to the receiver to eject its full contents.

Now when the action is reversed, and the emptying of the receiver again causes the float to drop and the slide valve again finally to lift again, the vent valve bellows must vent down to about 12 pounds, due to discharging pressure in the receiver which is never over 40 pounds, while the high pressure valve bellows is building up to 23 pounds; so that it is readily perceived that the high pressure valve will close before the vent valve opens, so that everything may be in readiness for the filling operation again. Hence just before the beginning of the discharging period when the receiver is full the vent valve closes first and the steam valve opens next, in this sequence; and when the receiver is empty through the action of the steam on the contents so as to start filling again the steam valve closes first and the vent valve opens, in this sequence. That is dur-

ing receiver-water discharge the steam valve is open and the vent valve closed; during receiver-water filling the steam valve is closed and the vent valve open. And before the discharge begins the vent valve closes before the steam valve opens; and before the filling begins the steam valve closes before the vent valve opens.

The difference in the effective areas of the bellows and the valves operated thereby controls the time and sequence of the closing of the valves. Obviously the bellows area will always be greater than the area of the valve which it actuates, but the ratio between the bellows and valve areas may vary very widely to suit different conditions, and I do not wish to be limited. The pressures may all vary within wide limits, in so far as it may be necessary to secure the best results in closing the vent valve before the steam valve opens and in closing the steam valve before the vent valve opens.

A further feature that is novel and useful is shown in Figure 3 and consists of a resilient buffer for the float G, which absorbs the shock if the float G drops so quickly as to violently strike against the bottom of receiver A, or against the top of same should it rise too suddenly, for such a sudden blow of the float against a solid wall might damage the valve mechanism. I avoid such a possibility by encircling the float G by an elliptical or oval spring steel band 70 which is spaced about the same distance from float G all around it and is supported by attachment to the float arm 27. While a single flat oval member of this kind, mounted in a vertical plane, will effectually protect the float by striking elastically any object toward which the float moves, and thus prevent the solid impact of the float against the receiver wall, yet if desired I can have more than one, several if desired, in different planes, vertical, horizontal, or angular.

A mode of mounting the spring shield at one end of float G, as on the arm 27, consists in having the hollow end of said arm filled in with a block 79 driven thereinto. On the end of arm 27 is a flanged casting 71 having a tubular socket 72 that receives the end of arm 27, which is secured therein by taper pin 73 or other suitable means. Also casting 71 has upper and lower flanges 78, and on the side opposite the socket 72 is a round projection 76 that enters a tubular socket 81 in the end 74 of float G. Moreover this socketed end of float G is flanged up and down at 77, said flanges being secured to the flanges 78 by means of rivets 75, the ends 80 of spring 70 being held tightly between flanges 77 and 78. Other means for mounting the elastic shield may be devised.

What I claim, is:

1. In an automatic receiver pump of the

class described, the combination of a liquid receiver having an inlet and outlet, a control valve and its cylinder, a buoyant member in the receiver, means whereby the buoyant member positively and automatically actuates said control valve, an exhaust outlet for the control cylinder, a steam inlet valve for the receiver, a steam outlet valve for the receiver, both controlling a common passage into the receiver, connections between the control valve and the steam inlet and outlet valves, said connections including expandable members which expand to close the steam inlet and outlet valves and contract to allow said valves to open, so that when the control valve is actuated in one direction the steam inlet valve will be opened and the outlet valve closed, and when the control valve is actuated in the opposite direction the inlet valve will be closed and the outlet valve opened.

2. In an automatic receiver pump of the class described, the combination of a liquid receiver having an inlet and outlet, a control valve and its cylinder, a buoyant member in the receiver, means whereby the buoyant member positively and automatically actuates said control valve, a steam inlet valve for the receiver having a stem, a steam outlet valve for the receiver having a stem, both valves controlling a common passage into the receiver, an expandable and contractible member engaging the steam valve stem to close said valve at times and allow it to open at other times, another expandable and contractible member engaging the steam outlet valve stem to close said valve at times and to allow it to open at other times, connections between the control valve cylinder and the said expandable and contractible members for conveying pressure to expand said members and to exhaust said pressure to permit them to contract when the pressure is released, and an exhaust for the control valve cylinder, all arranged so that when the control valve occupies one position the steam inlet valve will be opened and the outlet valve closed, and when the control valve occupies another position the steam inlet valve will be closed and the steam outlet valve opened.

3. In an automatic receiver pump of the class described, the combination of a liquid receiver having an inlet and outlet, a control valve and its cylinder, said valve consisting of a sliding port-provided block, a buoyant member in the receiver, means whereby the buoyant member positively and automatically actuates said control valve to cause it at one time to occupy the discharge position and at another time to occupy the filling position, a steam inlet valve for the receiver, a steam outlet valve for the receiver, both controlling a common passage into the receiver, an exhaust outlet for the control cylinder, connections between the control valve and the steam inlet and outlet valves, said connections including expandable members acting to close and open said inlet and outlet valves, accordingly as the control slide valve is actuated in one direction or the other.

4. In an automatic receiver pump of the class described, the combination of a liquid receiver having an inlet and an outlet, a control slide valve and its casing, a buoyant member in the receiver, means whereby the buoyant member positively and automatically actuates said control valve, an exhaust outlet for the control cylinder, a steam inlet valve for the receiver, a steam outlet valve for the receiver, both controlling a common passage into the receiver, an expansion unit acting to close the steam valve at one time and allow it to open under pressure at another time, a second expansion unit acting to close the outlet valve at one time and allow it to open under pressure at another time, means for conveying pressure from the control valve casing to the expansion units and for exhausting such pressure through the exhaust outlet, said means being controlled by the control valve, so that when the control valve is actuated in one direction the steam inlet valve will be opened and the outlet valve closed, and when the control valve is actuated in the opposite direction the inlet valve will be closed and the outlet valve opened.

5. In an automatic receiver pump of the class described, the combination of a liquid receiver having an inlet and an outlet, a control slide valve and its casing, said valve having a stem provided with collars that contact with and move the valve, said collars being spaced further apart than the length of the valve to give the rod a certain amount of movement without moving the valve, a float in the receiver, a lever connecting the float with the valve stem to actuate the latter, an exhaust outlet for the valve casing, a steam inlet valve for the receiver, a steam outlet valve for the receiver, both controlling a common passage into the receiver, an expansion unit arranged to close the steam valve, another expansion unit arranged to close the outlet valve, means for conveying pressure from the control valve casing to the expansion units and for exhausting such pressure through the exhaust outlet, said means controlled by the control valve, so that when the said valve is actuated in one direction the steam inlet valve will be opened and the outlet valve closed, and when the control valve is actuated in the opposite direction the inlet valve will be closed and the outlet valve opened.

6. In an automatic receiver pump of the class described, the combination of a liquid receiver having an inlet and outlet, a con-

- trol slide valve and its casing, said valve having a stem loosely connected with the valve so as to have some play without moving the valve, a float in the receiver, a lever connecting the float with the valve stem, so that the rise and fall of the float will shift the slide valve from discharge to filling position and the reverse, an exhaust outlet for the control casing, a steam inlet valve for the receiver, a steam outlet valve for the receiver, connections between the control valve and the said inlet and outlet valves including pressure-operated bellows that expand to close the valves and contract to allow them to open, so that when the control valve is lifted into filling position the steam valve will close and the outlet valve open in this sequence, and when the control valve is lowered to discharge position the outlet valve will be closed and the steam valve opened in this sequence. 70
7. In an automatic receiver pump of the class described, the combination of a liquid holding receiver having an inlet and outlet, a control slide valve and its casing, said valve having a stem provided with collars that contact with the valve above and below but are spaced further apart than the length of the valve to give the rod some movement without moving the valve, a float in the receiver, means connecting the float with the valve stem, an exhaust outlet for the valve casing, steam inlet and outlet valves for the receiver, having stems, expansion bellows loosely engaging said stems, means for conveying pressure from the control valve casing to said bellows and exhausting it in the exhaust outlet, so that when the bellows expand the valves will close and when they contract the valves will be allowed to open, all arranged so that when the float lifts the control valve into filling position the steam valve will close and the outlet valve open in this sequence, and when the float depresses the control valve into discharge position the outlet valve will close and the steam valve open in this sequence. 75
8. In an automatic receiver pump of the class described, the combination of a liquid holding receiver having an inlet and outlet, a control slide valve and its casing, said valve having a stem provided with upper and lower collars spaced further apart than the length of the valve, a float in the receiver, means connecting the float with the valve stem, an exhaust outlet for the valve casing, steam inlet and outlet valves for the receiver, stems for the said valves, bellows engaging said stems, which bellows expand to close said valves and contract to allow them to open, pipes for carrying pressure from the control valve casing to the bellows, said pipes having ports controlled by the control valve which at one time in one position admits high pressure to a pipe running to one bellows and simultaneously connects the other pipe to the exhaust, and at another time in another position admits high pressure to the other pipe running to the other bellows and simultaneously connects the other pipe with the exhaust, so that the float-actuated control valve will open and close said steam and outlet valves to automatically pump the water out of the receiver. 80
9. In an automatic receiver pump of the class described, the combination of a liquid holding receiver having an inlet and outlet, a head for said receiver having a pair of ports merging into a common passage into the receiver, one port to convey live steam to the receiver and the other to vent it from the receiver, a steam valve to deliver live steam to the steam port through an inlet port, a vent valve to allow exhaust steam to vent from its port through an outlet port, a casing for each valve containing steam pressure against the valve which opens the valve when closing pressure is reduced, expansion units that act against the valves with a closing pressure and contract to relieve said pressure to allow the valves to open, a float actuated control slide valve and its casing, means for conveying pressure from the control casing to the expansion units, and an exhaust outlet for the control casing. 85
10. In an automatic receiver pump of the class described, the combination of a liquid holding receiver having an inlet and outlet, a head for the receiver having ports merging into a common port into the receiver, one port to convey live steam to the receiver and the other to vent steam from the receiver, a steam valve to deliver live steam to the said steam port, a vent valve to allow exhaust steam to vent from the vent port, a casing for each valve containing steam pressure against the valve which opens the valve when closing pressure is reduced, expansion units that act against the valves with a closing pressure and contract to relieve said pressure to allow the valves to open, a control slide valve and its casing, a stem therefor having collars thereon to engage the valve above and below, and collars being spaced further apart than the length of the valve, a float, a lever carried thereby and pivoted to the valve stem, a fulcrum for the lever, means for conveying pressure from the control casing to the expansion units, and an exhaust outlet for the control casing, all operating so that when the float places control valve in filling position the steam valve will close and the outlet valve open in this sequence, and when the float places control valve in discharge position the outlet valve will close and the steam valve open in this sequence. 90
11. In an automatic receiver pump of the

class described, the combination of a liquid holding receiver having an inlet and outlet and ports merging into a common passage into the receiver, one port to convey live steam into the receiver and the other to vent it from the receiver, a steam valve to deliver live steam to said steam port, a vent valve to allow exhaust steam to vent from the vent port, said valves having valve stems, a casing for each valve containing steam pressure against the valve which opens the valve when closing pressure is reduced, expansion units that act against the valve stems with a closing pressure and contract to relieve said pressure to allow the valves to open, said units being of greater area than the valves, having lower pockets to loosely engage the upper ends of the valve stems, a float-actuated control slide valve and its casing, means for conveying pressure from the control casing to the expansion units, and an exhaust outlet for the control casing.

12. In an automatic receiver pump of the class described, the combination of a liquid holding receiver having an inlet and outlet, and ports merging into a common passage into the receiver, one port to convey live steam into the receiver and the other to vent it from the receiver, a steam valve to deliver live steam to said steam port, a vent valve to allow exhaust steam to vent from the vent port, a casing for the steam valve having a chamber receiving live steam from a supply, a chamber having an outlet into the receiver port, and a seat intermediate of the chambers on which the steam valve functions, a casing for the vent valve having a chamber with a discharge outlet, a chamber with a port through which the receiver vent port delivers, and a seat intermediate of the chambers on which the vent valve functions, each casing containing steam pressure against the valve which opens the latter when closing pressure is reduced, expansion units that act against the valves with a closing pressure and contract to relieve said pressure to allow the valves to open, a float actuated control slide valve and its casing, means for conveying pressure from the control casing to the expansion units, and an exhaust outlet for the control casing.

13. In an automatic receiver pump of the class described, the combination of a liquid receiver having an inlet and outlet, a control valve and its cylinder, a float in the receiver, a lever on the float to actuate the control valve, an exhaust outlet for the control cylinder, a steam inlet valve for the receiver, a steam outlet valve for the receiver, both controlling a common passage into the receiver, connections between the control valve and the steam inlet and outlet valves, said connections including expandable members which expand to close the valves and contract to

allow them to open, all arranged so that when the float lifts the control valve into filling position the steam valve will close and the outlet valve open in this sequence, and when the float depresses control valve into discharge position, the outlet valve will close and the steam valve open in this sequence.

14. In an automatic receiver pump of the class described, the combination of a liquid receiver having an inlet and outlet, a control cylinder having a high pressure inlet, an exhaust outlet, and a pair of high pressure outlets, a sliding control valve having a lateral port which functions with said outlets, so a stem for said valve having collars that engage with and move the valve, a float in the receiver, means connecting the float with the said valve stem, to cause the valve at one time to occupy the discharge position and at another time to occupy the filling position, a steam inlet valve for the receiver, a steam outlet valve for the receiver, both controlling a common passage into the receiver, expansion diaphragms acting to close the valves when expanded, pipes connecting said diaphragms with the control cylinder to convey pressure at times and exhaust at other times accordingly as the control slide valve is actuated.

15. In an automatic receiver pump of the class described, the combination of a liquid receiver having an inlet and outlet, a control valve and its cylinder, a float in the receiver provided with an elastic shield, a lever on the float to actuate the control valve, an exhaust outlet for the control cylinder, a steam inlet valve for the receiver, a steam outlet valve for the receiver, both controlling a common passage into the receiver, connections between the control valve and the steam inlet and outlet valves, said connections including expandable members which expand to close the valves and contract to allow them to open, all arranged so that when the float lifts the control valve into filling position the steam valve will close and the outlet valve open in this sequence, and when the float depresses the control valve into discharge position, the outlet valve will close and the steam valve open in this sequence.

16. In an automatic receiver pump of the class described, the combination of a liquid receiver having an inlet and outlet, a control cylinder having a high pressure inlet, an exhaust outlet, and a pair of high pressure outlets, a sliding control valve having a lateral port which functions with said outlets, a stem for said valve having collars that engage with and move the valve, a float in the receiver provided with an elastic shield, means connecting the float with the said valve stem, to cause the valve at one time to occupy the discharge position and

at another time to occupy the filling position, a steam inlet valve for the receiver, a steam outlet valve for the receiver, both controlling a common passage into the receiver, expansion diaphragms acting to close the valves when expanded, pipes connecting said diaphragms with the control cylinder to

convey pressure at times and exhaust at other times accordingly as the control slide valve is actuated.
